FLASHER

Carl H. Larson, Elkhart, Ind., assignor to The
Adlake Company, a corporation of Illinois

Application December 29, 1934, Serial No. 759,634

11 Claims. (Cl. 177—329)

Highway crossing signals, particularly those used at railway crossings, must be highly reliable, because the public is inclined to trust them implicitly. Unfortunately, however, no signal is infallible, and the aim of the present invention is to minimize the danger that results from improper signal operation, as for example when the control circuit fails, or when a lamp burns out.

Further and other objects and advantages 10 will become apparent as the disclosure proceeds and the description is read in conjunction with the accompanying drawings, in which

Fig. 1 is a diagrammatic view of a flasher made in accordance with this invention, the switch parts being shown in the position they assume just prior to the energization of the control switch;

Fig. 2 is a similar view, but showing the switch parts in the position they assume just prior to de- 20 energization of the control switch;

Fig. 3 is a similar view showing the position of the switch parts when the control circuit is dead, as for example when a fuse in the control circuit has been blown;

25 Fig. 4 illustrates what takes place when the control switch is stuck in energized position;

Fig. 5 illustrates the condition of the circuit when the control switch is stuck in its raised position, as for example when a short circuit 30 maintains the associated magnets energized;

Fig. 6 is a rear perspective view showing the physical form of the flasher relay;

Fig. 7 is a horizontal, sectional view taken on the line 7—7 of Fig. 6.

35 It will be understood that the embodiment of the invention shown in the drawings and the specific description which follows are for the purpose of disclosure only and should not be construed as imposing limitations on the appended 40 claims except as may be required by the prior art.

PHYSICAL RELAY

Before describing the circuits used in the flasher relay of this invention, it may be helpful to first understand its physical form.

45 The relay is housed within a casing 10 (Figs. 6 and 7) open at the back and having a vertical flange 11 provided with keyhole slots 12 (only one is shown) for securing the relay to a suitable support. The operative parts of the relay are mounted on a panel 13 which closes the front of the casing 10 and carries a plurality of relay coils 14, the upper two being associated with a top pole piece 15, and the lower two being associated 50 with a bottom pole piece 16, both of magnetic ma-

terial. The details of mounting the coils on the panel 13 are unimportant here, and no further description is necessary except to point out that the relay coils 14 have iron cores 17 which, with external iron connectors 18 and the pole pieces 15 and 16, form a magnetic circuit that is closed except for the air gap between the poles 15 and 16. 5

The poles 15 and 16 have vertical aligned apertures 19, 20 and 21 adapted to receive a control circuit breaker or switch 22, and lamp circuit 10 breakers 23 and 24, respectively.

The exact location of the air gap between the poles 15 and 16 is very important in obtaining proper relay characteristics, and to this end, iron sleeves 25 are telescoped over the circuit breakers 15 23 and 24 to fix the position of the air gap. The construction of the control switch 22 is such that an iron sleeve is not necessary. Spacer sleeves 26 of non-magnetic material are also telescoped over the circuit breakers 23 and 24 to protect the 20 otherwise exposed portions of the circuit breakers and to hold the iron sleeves 25 in place. These sleeves, as well as a similar sleeve of non-magnetic material telescoped over the control switch 22, serve the additional purpose of frictionally holding the switches in place within the 25 iron circuit.

THE CIRCUIT BREAKERS

A. Control switch 22

30

The control switch 22 is a slow acting back contact switch (Fig. 1) and comprises a switch envelope 30, preferably of glass, through the bottom of which electrodes 31 and 32 are sealed. 35 The central electrode 31 is surrounded by a glass insulating sleeve 33 for a portion of its length and the bared end of the electrode is bent over with its end 34 alongside the insulating sleeve 33.

The envelope contains a quantity of mercury 40 35 which is adapted under certain conditions to bridge the electrodes 31 and 32.

A displacer 36 determines by its position within the switch envelope the level of the mercury and consequently the condition of the circuit through 45 the switch. It comprises a sleeve 37 of magnetic material closed at its top by a thimble 38 of porous material. Preferably, the thimble is made of a ceramic material, known as "alundum," which is manufactured by the Norton Company 50 of Worcester, Massachusetts. One of the three principal grades, R-A-84 Dense, R-A-360 Medium and R-A-98 Coarse, may be selected according to the specification of the switch.

The rate of gas flow through the thimble may 55

be more accurately adjusted by applying dabs of cement to the thimble.

The plunger is guided in its vertical movement by washers 39 having three or more smoothly rounded lugs 40 engaging the walls of the envelope. The washers are held in place by springs 41 which serve to protect the switch envelope during shipping.

Before the switch envelope is sealed off at 42, it is evacuated and filled with an inert, or arc suppressing, gas (helium, hydrogen, helium hydride, or the like).

The displacer 36 of the control switch 22 is adapted to reciprocate within the switch envelope at a predetermined rate of oscillation and in Fig. 1, the switch parts are shown in the position which they assume just before the circuit through the electrodes 31 and 32 is closed. It will be noticed that the mercury level on the outside of the displacer 36 is slightly higher than the mercury level on the inside of the displacer, this difference in level producing a slight gas pressure differential between the gas trapped within the displacer and that on the outside. As the gas pressures tend to become equalized by the slow outward passage of gas through the porous wall of the thimble 38, the mercury level on the inside of the displacer slowly rises and that on the outside slowly falls. As soon as the inside mercury level reaches the end 34 of the electrode 31, the circuit through the switch is closed and the relay coils 14 become energized. The displacer is then lifted to the position shown in Fig. 2 drawing up with it a column of mercury to a height such as indicated by the dotted line 43. Again, there is a gas pressure differential between the gas in the inside of the displacer and that on the outside, but in this case, the greater pressure is on the outside of the displacer so that there is a slow seepage of gas into the displacer. As the gas pressures tend to become equalized, the mercury level on the inside of the displacer gradually falls and that on the outside gradually rises until the inside mercury level falls below the end 34 of the electrode 31, whereupon the relay coils 14 become de-energized and the displacer falls by gravity to the position shown in Fig. 1, forcing the mercury level on the inside down to the position indicated by the dotted line 44 (Fig. 1).

The above functioning of the control switch classifies it as of the self-acting intermittent type, i. e., it automatically interrupts its own circuit.

In Fig. 2, the control switch 22 is shown just before the circuit between the electrodes 31 and 32 is opened by the receding mercury column within the displacer.

B. Lamp circuit breaker 23

The lamp circuit breaker 23 is similar in many respects to the control circuit breaker 22, but it functions quite differently. It comprises a switch envelope 45, electrodes 46 and 47, a mercury fill 48 and a displacer generally designated 49, but the electrode 46 is somewhat shorter than the electrode 31, and the mercury fill 48 is such that when the displacer 49 is completely out of the mercury as shown in Fig. 2, the circuit through the switch is closed.

The displacer 49 comprises an iron sleeve 50 interiorly fitted with an elongated glass thimble 51 having a small opening 52 in its top wall. The thimble is held in place within the iron sleeve 50 by springs 53 which frictionally engage the ends

of the thimble which project beyond the iron sleeve and which also clamp guide washers 54 in place.

The top of the thimble 51 is packed with cotton wads 55 and 56, and between the two wads 5 is a quantity of ceramic powder 57. The two cotton wads and the powder serve the same purpose as the ceramic thimble 38 in the control switch 22, i. e. they provide for a restricted flow of gas between the inside and outside of the 10 displacers. The exact rate of flow in the lamp circuit breaker 23 may be adjusted by the quantities of ceramic powder and cotton used and the tightness with which they are packed into the thimble. 15

The lamp circuit breaker 23 functions as a front contact switch as long as the intermittent energization of the relay coils 14 continues above a predetermined frequency. In such a case, the circuit through the switch is closed 20 whenever the coils 14 are energized, see Fig. 2, and any mercury within the displacer when the latter is lifted by the coils 14 falls away as soon as the outside mercury level drops below the bottom of the sleeve 51. 25

When the coils 14 are de-energized, the displacer falls by gravity to the position shown in Fig. 1 forcing the mercury away from the central electrode 46 due to the compression of gas within the displacer. The time delay element 30 at the top of the displacer is adjusted so that before the inside mercury level has a chance to make contact with the electrode 46 due to equalization of the gas pressures on the inside and outside of the displacer, the coils 14 have again 35 become energized causing the displacer to be lifted to the position shown in Fig. 2.

If, however, the coils 14 are not energized within the time which it takes for the inside mercury level to reach the central electrode 46, it 40 is obvious that the circuit through the electrodes 46 and 47 will be closed.

C. The lamp circuit breaker 24

This circuit breaker normally functions as a 45 back contact switch, but in case the intermittent energization of the coils 14 falls below the pre-determined frequency, or in case a short circuit causes the coils to be continuously energized, the switch then functions as a front contact switch 50 and closes the circuit through the switch.

The switch comprises a glass envelope 58, electrodes 59 and 60, a mercury fill 61 and a displacer generally designated 62, and in general these parts resemble the corresponding parts of 55 the two switches which have already been described. The displacer 62 is substantially identical with the displacer 49 of the lamp circuit breaker 23, and in so far as the parts are the same, they will be given corresponding reference 60 characteristics, and will not be further described.

The principal difference between the displacer 62 of the lamp circuit breaker 24 and the displacer 49 of the lamp circuit breaker 23 is that the former is provided with an opening 63 65 through its side wall. As will be seen from Fig. 1 when the switch 24 is in its de-energized position, the circuit through the electrodes 59 and 60 is closed, the displacer then being in its uppermost position and the openings 63 being just 70 above the mercury level. When the coils 14 are energized, the displacer is pulled down to the position shown in Fig. 2 and the gas entrapped within the displacer forces the inside mercury level away from the bared end of the electrode 75

59, thus causing the circuit through the switch to be opened. As gas slowly escapes through the time delay element from the inside of the displacer to the outside when the mercury level 5 within the displacer gradually rises but before it has a chance to make contact with the electrode 59, the relay coils 14 become de-energized if the control circuit is working properly and the plunger 62 is lifted by its buoyancy to the position shown in Fig. 1, and any mercury which is carried up within the displacer during its upward movement falls away as soon as the opening 63 rises above the outside mercury level so that the mercury automatically levels off whenever the relay coils 14 become de-energized.

Should the relay coils 14 for some reason fail to become de-energized within the period prescribed by the time element at the top of the displacer 62, the mercury on the inside of the displacer will rise and make contact with the electrode 59, thus completing the circuit through the switch.

THE CIRCUITS

A. The control circuit

The control circuit is shown in light lines and functions to intermittently energize the relay coils 14. When the flasher is used at a railroad crossing, the local circuit is placed in operation whenever a train enters a given section of track and short circuits the track relay 70 which includes a back contact switch 71 associated with the control circuit and a back contact switch 72 associated with the lamp circuit. The control circuit in practice is ordinarily energized by a battery 73 and the control switch 22 and relay coils 14 (connected in parallel) are in series with a battery 73 and the back contact switch 71 of the track relay. The circuit can be traced from the battery 73 through a conductor 74, switch 71, conductor 75, electrode 31, mercury 35, electrode 32, conductors 76 and 77 to the relay coils 14 (the coils are connected in parallel with one another) and back to the battery 45 through conductor 78.

This circuit makes the control switch 22 a self-acting intermittent circuit breaker whose rate of oscillation is determined by the rate of gas flow through the time delay element 38.

B. Lamp circuit

The lamp circuit is shown in heavy lines and includes the lamp circuit breakers 23 and 24, lamps 80 and 81, the back contact switch 72 of the track relay 70 and the secondary coil 82 of a transformer 83 which in practice is ordinarily energized from a 110 volt alternating current line.

The lamp 80 is controlled by the circuit breaker 60 23 and the lamp 81 by the circuit breaker 24 and when the coils 14 are de-energized (as in Fig. 1) the circuit through the lamp 81 may be traced from the secondary coil 82 of the transformer 83 through conductor 84, conductor 85, electrode 65 60 of the switch 24, mercury 61, electrode 59, conductor 86, lamp 81, conductor 87, back contact switch 72 of the track relay 70, and back to the secondary coil 82 through conductor 88.

When the relay coils 14 are energized, as in Fig. 2, the circuit through the lamp 80 may be traced from the secondary coil 82 of the transformer 83 through the conductor 84, conductor 89, electrode 47 of the switch 23, mercury 48, electrode 46, conductor 90, lamp 80, conductor 87, 75 back contact switch 72 of the track relay 70 and

back to the secondary coil 82 through conductor 88.

OPERATION

It has been pointed out that the control switch 22 functions as a self-acting intermittent circuit breaker controlling the intermittent energization of the relay coils 14 which in turn actuate the lamp circuit breakers 23 and 24, one of which functions as a back contact relay and the other as a front contact relay. As long as the coils 14 are intermittently energized above a predetermined frequency, the lamps 80 and 81 will be alternately illuminated and the desired flashing signal indication will be obtained.

Now let us suppose that for some reason, the control circuit should fail, as for example by the blowing of a fuse 91 (Fig. 3). The relay coils 14 then become permanently de-energized as distinguished from intermittently de-energized, and the circuit breakers 23 and 24 take 20 the position shown in Fig. 3, in which the electrical circuits through both switches are closed.

Under these conditions, when a train approaches a protected crossing, the back contact switch 72 of the track relay 70 is closed and both of the lamps 80 and 81 illuminated. This circuit relationship is particularly desirable because it illuminates both lamps in case the control circuit fails, and should one lamp be burned out, the other one will still be illuminated. If an ordinary front contact switch were used in place of the circuit breaker 23 and should the lamp 81 be burned out when the control circuit failed, there would be no signal indication.

Another abnormal condition which may occur is for the control switch 22 to be stuck in energized position, as for example when the current in the local circuit is insufficient to lift the displacer. In such a case, the coils 14 stay energized, and if the magnetic flux which they produce is sufficient to operate the circuit breakers 23 and 24, the switch parts will take the position shown in Fig. 4, or if the flux is not sufficient to move the displacers, they will take the positions shown in Fig. 3. In either case, the circuits through both of the lamps 80 and 81 are closed because whenever the displacers 49 and 62 are held in any position for more than a predetermined time interval, the circuits through the respective switches will be closed. Here again, 50 therefore, an additional safety factor is furnished because the circuits through both lamps are closed.

There are other conditions which might exist to cause the intermittent operation of the lamp circuit breakers 23 and 24 to cease. For example, there might be a short circuit in the control circuit which would cut the control switch 22 from the remainder of the circuit and thus cause the relay coils 14 to be permanently energized. 60 This would occur in case the wires 74 and 77 became crossed. The lamp circuit breakers would then hold the position shown in Fig. 4 and the circuits through both lamps would be closed.

It might also happen that some mechanical 65 injury to the switch would prevent the displacer 36 of the control switch 22 from falling in which case the lamp circuit breakers 23 and 24 would take the position shown in Fig. 1. Again, however, the circuits through both lamps are closed. 70

It will thus be seen that the flashing signal of this invention will provide a warning signal as long as the lamp circuits have an electromotive force, and one or the other of the lamps 80 and 81 are operative. The failure of the control cir- 75

cuit by any one of a number of possible causes only stops the alternate flashing of the lamps, and when this condition exists, the circuits through both lamps are closed. This is a distinct advantage over flasher relays now on the market.

When the principles underlying the invention are fully understood, many modifications will suggest themselves to those skilled in the art and the appended claims are to be construed as broadly as the prior art will permit.

For convenience the switches 23 and 24 will be identified in the appended claims according to their normal functions, i. e., the switch 23 will be called a front contact switch and the switch 24 a back contact switch.

The following glossary of terms will serve to indicate the intended connotations for the terms: Circuit breaker—a switch for selectively bridging a gap between two adjacent conductors which 20 form a part of an electrical circuit; front contact circuit breaker—a circuit breaker as defined above which is operated by an electrical device which when energized bridges or tends to bridge the gap between the adjacent conductors 25 associated with the circuit breaker; back contact circuit breaker—a circuit breaker as defined above which is operated by an electrical device which when deenergized bridges or tends to bridge the gap between the adjacent conductors 30 associated with the circuit breaker; synchronism—the timed relationship between two or more things which operate either simultaneously or in cycles which bear a timed relationship with each other.

35 I claim as my invention:

1. In a device of the class described, a control circuit including a self-acting intermittent circuit breaker, a main circuit including a pair of lamps, means alternately illuminating of the 40 lamps comprising a front contact circuit breaker associated with one lamp and a back contact circuit breaker associated with the other lamp, means in the control circuit for operating the lamp circuit breakers in synchronism with the control circuit breaker, and means for closing 45 the circuit through one of the lamp circuit breakers whenever that one fails to operate above a predetermined minimum number of cycles per unit of time.

50 2. In a device of the class described, a control circuit including a self-acting intermittent circuit breaker, a main circuit including a pair of lamps, front and back contact switch means associated with the lamps, means for alternately illuminating the lamps in response to the contact switch means, means in the control circuit for operating the contact switch means in synchronism with the circuit breaker, and means for closing the 55 circuit through at least one of the lamp switch means whenever the time rate of operation of said one switch means falls below a predetermined value.

60 3. In a device of the class described, a control circuit including a self-acting intermittent circuit breaker, a main circuit including a pair of lamps, front and back contact switch means associated with the lamps, means for alternately illuminating the lamps in response to the contact switch means, means in the control circuit for operating the contact switch means in synchronism with the circuit breaker, and means for closing the 65 circuit through the switch means whenever the switch means fails to operate above a predetermined minimum number of cycles per unit 70 of time.

4. In a device of the class described, a control circuit including a self-acting intermittent circuit breaker, a main circuit including a pair of lamps, means for alternately illuminating the lamps including front and back contact switches 5 associated with the lamps and operable in response to and in synchronism with the control circuit breaker, and means including a time delay element constructed and arranged to illuminate both lamps in case the control circuit breaker 10 fails to operate.

5. In a device of the class described, an intermittently energized control circuit, a main circuit including a pair of lamps, means for alternately illuminating the lamps in response to and 15 in synchronism with the intermittent energization of the control circuit, and means including a time delay element constructed and arranged to illuminate at least one of the lamps in case the intermittent energization of the control circuit 20 fails irrespective of whether the failure of the circuit is due to permanent energization or permanent de-energization of the control circuit.

6. In a device of the class described, an intermittently energized control circuit, a main circuit including a pair of lamps, means for alternately illuminating the lamps in response to and 25 in synchronism with the intermittent energization of the control circuit, and means for illuminating at least one of the lamps in case the intermittent energization of the control circuit fails, 30 said means including a switch in the main circuit having a time delay element constructed and arranged so that if given sufficient time to operate will close the circuit through the switch regardless of the position of the switch parts within their range of relative movement and irrespective of whether the failure of the circuit is due to permanent energization or permanent de-energization of the control circuit. 35

7. In a device of the class described, an intermittently energized control circuit, a main circuit including a pair of lamps, means including a front contact switch and a back contact switch for alternately illuminating the lamps in response 40 to and in synchronism with the intermittent energization of the control circuit, and means for illuminating both of the lamps in case the intermittent energization of the control circuit falls below a predetermined frequency. 45

8. In a device of the class described, a flux responsive switch breaking upon de-energization and again closing after a short period of time during said de-energization, a flux responsive switch breaking upon energization and again closing after a short period of time during said 55 energization, flux inducing means alternately simultaneously energizing and de-energizing said switches at predetermined intervals, and signal means effective during the closure of the switches 60 controlled by each switch.

9. In a device of the class described, a flux responsive normally closed switch breaking upon de-energization and again closing after a short period of time, a flux responsive normally closed 65 switch breaking upon energization and again closing after a short period of time, flux inducing means energizing and de-energizing said switches in timed relation simultaneously, and signal means effective during the closure of the 70 switches controlled by each switch.

10. In a device of the class described, a flux responsive normally closed switch breaking upon de-energization and returning to normal condition after a short period of time, a flux respon- 75

sive normally closed switch breaking upon energization and returning to normal condition after a short period of time, flux inducing means for energizing and de-energizing said switches in timed relation simultaneously, and signal means effective during the closure of the switches controlled by each switch.

5. 11. In a device of the class described, a flux responsive quick breaking switch closing after a

period of energization, a flux responsive quick breaking switch closing after a period of de-energization, flux inducing means energizing and de-energizing said switches at timed intervals simultaneously, and signal means effective during the closure of the switches controlled by each switch.

CARL H. LARSON.
